DESIGN FOR A WHEEL

J Harold Hunt, Lansing, Mich., assignor to Motor Wheel Corporation, Lansing, Mich., a corporation of Michigan

Application June 7, 1934, Serial No. 52,089

Term of patent 7 years

To all whom it may concern:

Be it known that I, J Harold Hunt, a citizen of the United States, residing at Lansing, in the county of Ingham and State of Michigan, have invented a new, original, and ornamental Design for a Wheel, of which the following is a specification, reference being had to the accompanying drawing, forming part thereof.

In the drawing:

Figure I is a side view of a wheel showing my new design;

Figure II is a perspective view of the wheel shown in Figure I;

Figure III is an enlarged sectional profile view through a spoke taken on substantially the line III—III of Figure I; and

Figure IV is an enlarged sectional profile view taken on substantially the line IV—IV of Figure I.

The characteristic feature of this design resides in a wheel as shown having a central annular bead about the hub cap receiving opening.

I claim:

The ornamental design for a wheel, as shown and described.

J HAROLD HUNT.
